UNITED STATES PATENT OFFICE.

EDWARD K. TOLMAN, OF WORCESTER, MASSACHUSETTS.

REGISTERING AND CANCELING BALLOT-BOX.

No. 807,882.

Specification of Letters Patent.

Patented Dec. 19, 1905.

Application filed April 24, 1905. Serial No. 257,033.

To all whom it may concern:

Be it known that I, EDWARD K. TOLMAN, a citizen of the United States, residing at Worcester, in the county of Worcester and 5 Commonwealth of Massachusetts, have invented a new and useful Improvement in Registering and Canceling Ballot-Boxes, of which the following is a specification, accompanied by drawings forming a part of the 10 same, in which—

Figure 1 represents a top view of a ballot-box embodying my invention. Fig. 2 is a side elevation of the same. Fig. 3 is a longitudinal central sectional view on line 3—3, 15 Fig. 1, showing the operative parts of the apparatus in their normal position. Fig. 4 is a longitudinal central sectional view on line 3—3, Fig. 1, but showing the operative parts of the apparatus in their position during the passage of a ballot through the apparatus. Fig. 20 5, 6, and 7 are detailed views showing the rack- and - pinion mechanism for operating the registering device in different positions.

Similar reference-figures refer to similar 25 parts in the different views.

My invention relates to a self-registering and canceling ballot-box by which individual ballots as fed are received, canceled, and registered, and it comprises individual features 30 of construction and arrangement of parts for the accomplishment of these objects and for obviating the liability of error in the operation of the apparatus, and it has also for its further object to simplify the construction of 35 the apparatus and to render the operation of the several parts accurate and certain; and to this end my invention consists in the construction and arrangement of parts as hereinafter described, and pointed out in the annexed claims.

Referring to the accompanying drawings, 1 represents a supporting-framework capable of being suitably supported upon a box or casing 2, partially shown in Figs. 2, 3, and 4, 45 in which the ballots after passing through the apparatus and being registered and canceled, are deposited. Supported by the framework 1 is an inclined feed-board 3, upon which the ballot is deposited by the voter 50 face downward and upon which it is pushed forward by hand until its advancing end is caught between the peripheries of the rolls 4 and 5. The roll 4 is attached to a rotating shaft 6, having one end projecting beyond 55 the frame and provided with a crank-handle 7, by which the roll 4 is rotated in the di-

rection of the arrow 8, causing the ballot to be drawn from the feed-board 3 between the rolls 4 and 5. The roll 5 is attached to a shaft 9, which is journaled in the free ends 60 of swinging levers 10 10, which are pivoted at their opposite ends upon a rod 11, held in the framework of the machine. Attached to each of the levers 10 10 are blade-springs 12, having their ends bearing upon fixed studs 65 13 held, in the frame 1, with the tension of the blade-springs 12 applied to depress the free ends of the levers 10 to press the roll 5 against the roll 4 and preventing the slipping of the ballot as it passes between the rolls. 70 The rolls 4 and 5 are grooved to admit a series of rolls 14, carried upon a shaft 15, which is journaled in a swinging frame 16, pivoted at 17 to the frame 1. The swinging frame 16 carries a stud 18, which passes through a slot 75 19 in the frame 1, which limits the swinging movement of the frame 16, the stud 18 being normally held at the bottom of the slot by the weight of the swinging frame and the rolls 14, with the edges of the rolls 14 entering the 80 grooves of the roll 4. The central roll 14 is provided with a series of projections which in the present instance are molded upon a rubber band 20, placed upon the periphery of the roll and adapted to be inked by an ink- 85 ing-roll 21, journaled in a swinging frame 22, pivoted to the frame 1 at 23, with the free end of the frame 22 resting against a fixed stud 24, held in the frame 1, against which stud the frame 22 is held by the tension of a 90 spiral spring 25, attached at one end to the swinging frame 22 and at the opposite end to the fixed frame 1.

Supported beneath the inking-roll 21 and upon a bracket 26 is a pan 27 to prevent the 95 dripping or spattering of surplus ink downward into the box or ballot-receptacle 2. Pivoted upon the rod 11 is a tilting guard-wire 28, having a short arm 29 extending horizontally over the feed-board 3, and a longer 100 arm 30 passing downward through a slot 31 in the feed-board. As a ballot is fed over the feed-board, its advancing end, striking the long depending-arm 30 of the tilting guard-wire, raises it into the position shown in Fig. 105 4, thereby depressing the short arm 29 against the upper surface of the ballot, which is pushed by the pressure of the arm 29 into a trough-shaped depression 32, formed in the upper surface of the feed-board 3, thereby 110 causing the ballot to be depressed below the plane of the supporting-surface of the feed-

board. As the ballot is moved forward between the rolls 4 and 5 it is projected between the rolls 4 and 14, causing the rolls 14 to be lifted into the position shown in Fig. 4, and 5 carrying the band 20 of the central roll 14 against the inking-roll 21, so that the ink transferred to the rubber band will be applied to cancel the ballot. The swinging frame 16, which carries the rolls 14, supports 10 at its free end a bent wire 33, having its end turned upwardly at 34 and adapted to pass through the slot 31 in the feed-board as the rolls 14 are raised by the ballot in the position shown in Fig. 4, thereby raising that 15 portion of the ballot from the feed-board and lifting the ballot against the pressure of the arm 29 of the tilting guard-wire 28, and also against the lower edges of a pair of plates 35, which are pivoted upon the rod 11, and are 20 held in an inclined plane with their lower edges resting upon the feed-board. The plates 35 are slightly inclined to the surface of the feed-board in a direction to permit the forward movement of the ballot over the feed-board, but resist the backward movement of the ballot by the engagement of the lower edges of the plates therewith, the plates then acting as ratchets to prevent the ballot from being pulled backward. Each of the 25 ratchet-plates 35 is provided with a weight 36 to hold the plate in firmer contact with the surface of the ballot.

Supported by the framework 1 is a registering mechanism capable of being actuated 30 by a swinging pawl-lever 36^a, which is held in its normal position by a spring 37. The registering mechanism may be of any known form of construction, and as it forms no part of my present invention I have not deemed 35 it necessary to describe its construction and operation in detail. The pawl-lever 36^a is intermittently rocked in the direction of the arrow 38 and against the tension of the spring 37 during the passage of a ballot between the 40 rolls 4 and 5 by means of a push-rod 39, pivoted to the pawl-lever 36^a and provided with a rack 40 at its opposite end capable of sliding on a pin 40^a, held in a pivoted lever 41, pivoted at 42 upon the fixed framework 1 45 and connected at its free end by a link 43 with the stud 18, which is carried by the swinging frame 16. As the swinging frame 16 is raised by the passage of a ballot between rolls 4 and 14 the lever 41 is rocked on 50 its pivot to bring the rack 40 into engagement with a pinion 44, carried on the main shaft 6. The rotation of the pinion 44 in the direction of the arrow 8, Fig. 2, will cause the push-rod 39 to be moved in the direction of 55 the arrow 45, thereby rocking the pawl-lever 36^a in the direction of the arrow 38 to actuate the registering device. When the rack 40 has been moved a sufficient distance to 60 actuate the registering device, its shoulder 46 65 is carried past the pin 40^a, which allows the

rack to fall by gravity and carry it out of engagement with the pinion 44. The engagement of the pin 40^a with the shoulder 46 then holds the rack from reverse movement until the ballot has entirely passed between the rolls 4 and 14, when the weight of the rolls 14 carry them downward into their normal position and again depress the pivoted lever 41. As the lever 41 is depressed the push-rod 39 strikes against a hub 47 on the lever 41, causing the shoulder 46 to be disengaged from the stop-pin 40^a, when the tension of the spring 37 reverses the pawl-lever 36^a and carries the rack 40 into its normal position, as shown in Fig. 2. 70 75 80

Attached in any convenient position upon the side of the framework is a bell 48, capable of being struck by a hammer 49, which is pivoted at 50 upon the side of the frame and is normally held out of contact with the bell. 85 The pivoted hammer is provided with a tail-piece 51, adapted to be struck by a bracket 52, attached to the push-rod 39, with sufficient force to overcome the weight of the hammer 49 and throw it against the bell 48. 90 As soon as the hammer has struck the bell 48 its weight restores it to its normal position with the tailpiece 51 resting against the bracket 52. Pivoted eccentrically at 53 upon the frame 1 is a roller 54 with its periphery in contact with the roll 4 in order to 95 prevent its reverse movement.

The line 55, Fig. 4, indicates the position of a ballot when passing through the machine and before it has been withdrawn from the feed-board 3, said ballot being engaged by the feed-rolls 4 and 5 and spanning the grooves in the roll 4, causing the series of rolls 14 to be raised for the purpose of lifting the swinging rack 40 into engagement with the rotating pinion 44 and at the same time carry the canceling characters on the band 20 into contact with the inking-roll 21, which is capable of a yielding motion due to the swinging frame 22 and spiral spring 25. In 100 the position shown in Fig. 4 the ballot is depressed by the arm 29 into the depression 32 of the feed-board and is raised from the feed-board by the end 34 of the bent wire 33. 105 110 115

What I claim as my invention, and desire to secure by Letters Patent, is—

1. The combination with a feed-board on which a ballot is presented to the machine, said feed-board having a depression in its upper surface, of means for depressing the ballot as it passes over the depressed surface of the feed-table. 120

2. The combination with a feed-board on which a ballot is presented to the machine, said feed-board having a depression in its upper surface, of a tilting guard-wire arranged to depress a ballot as it passes over said depression, and means for actuating said guard-wire determined by the passage of a ballot through the machine. 125 130

3. The combination with a feed-board, on which a ballot is presented to the machine, said feed-board having a depression in its upper surface, of a tilting guard-wire pivotally supported above said feed-board, and having an arm extending over said depressed surface, and an arm extending into the path of the ballot as it moves over said feed-board, whereby said guard-wire is actuated.
4. The combination with a feed-board on which a ballot is presented to the machine, said feed-board having a depression in its upper surface, a pair of rolls by which a ballot is drawn over said feed-board, a tilting guard-wire pivoted above said feed-board and having an arm for depressing a ballot into the depression of the feed-board, and a second arm interposed into the path of a ballot as it is drawn from the feed-board.
5. The combination with a feed-board on which a ballot is presented to the machine, said feed-board having a depression in its upper surface, of a pair of rolls for drawing the ballot from the feed-board, of a tilting guard-wire pivoted above said feed-board having one arm extending over the upper surface of the feed-board, and a second arm extending downward into the path of the ballot as it is moved from the feed-board, and a pair of weighted ratchet-plates pivotally supported above the feed-board and arranged to bear on a ballot adjacent to the depressed surface of said feed-board.
6. The combination with a feed-board on which a ballot is presented to the machine, said feed-board having a depression in its upper surface, of means for depressing a ballot as it passes over said depressed surface and means for holding the ballot in contact with the feed-board adjacent to said depressed surface.
7. The combination with a feed-board on which a ballot is presented to the machine, said feed-board having a depression in its upper surface, of means for depressing a ballot as it passes over said depressed surface, means for pressing the ballot against the feed-board behind said depressed surface and intermediate means for lifting the ballot from the feed-board.
8. The combination with a feed-board on which a ballot is presented to the machine, of a pair of rolls for engaging the ballot to draw it from said feed-board, the rolls of said pair having corresponding grooves, and a series of rolls entering the grooves of said pair of rolls, a common shaft supporting said series of rolls and a swinging frame supporting said shaft, whereby said series of rolls are capable of a rising and falling motion.
9. The combination with a pair of grooved rolls for feeding a ballot into the machine, of a series of rolls normally entering the grooves in said feed-rolls, whereby they are raised by the passage of a ballot, a swinging frame car-
- rying said series of rolls, a registering device and intermediate mechanism operatively connecting said registering mechanism and said swinging frame.
10. The combination with a pair of grooved feed-rolls, of a series of rolls entering the grooves of said feed-rolls, and capable of being lifted by the passage of a ballot, canceling characters carried by one of the rolls in said series and an ink-roll running in contact with said characters.
11. The combination with a feed-board having an opening and a grooved roll forming one of a pair of ballot-feeding rolls, of a series of rolls entering the grooves of said feed-roll and arranged to be lifted out of said grooves by the passage of a ballot, a swinging frame carrying said series of rolls, and a bent guard-wire carried by said swinging frame and adapted to be raised through the opening in said feed-board.
12. The combination with a pair of feed-rolls, of a series of rolls adapted to be raised by the passage of a ballot, a common shaft carrying said rolls, a swinging frame carrying said shaft, means for limiting the downward movement of said frame, and a bent guard-wire carried by said swinging frame and arranged to be raised in front of said feed-rolls to prevent the passage of a second ballot while said rolls are in a raised position.
13. The combination of a pair of feed-rolls provided with corresponding grooves and a roll entering said grooves but capable of being moved out of said grooves by the passage of a ballot, canceling characters on said roll and an ink-roll running in contact with said characters.
14. The combination with a main rotating shaft and a pinion carried on said shaft, of a registering device, a swinging-pawl lever for actuating said registering device, and means for operatively connecting said pawl-lever with said pinion as determined by the passage of a ballot through the machine and consisting of a link pivoted to said pawl-lever, a rack carried by said link, a lever pivoted to the framework, a pin carried by said lever and extending beneath said rack, a swinging frame arranged to be raised by a passing ballot, and a link connecting said swinging frame and said pivoted lever.
15. The combination with a pair of grooved feed-rolls, of a swinging frame, a roll carried by said swinging frame and normally entering one of the grooved feed-rolls, and arranged to be raised by a passing ballot, a rotating pinion, a swinging rack, a pivoted lever, a pin carried by said pivoted lever and extending beneath said rack, a link connecting said pivoted lever and said swinging frame, a registering device, and means for operatively connecting said rack and said registering device.
16. The combination with a pair of feed-

- 4
- rolls, of a pinion carried on the shaft of one of the feed-rolls, a registering device comprising a swinging pawl-lever, a link pivoted to said pawl-lever, a rack carried by the end of 5 said link and provided with a notch on its under side, a lever pivoted to the frame, a pin carried by said lever and arranged to support said rack, and means for rocking said lever to carry the rack into engagement with 10 said pinion as determined by the passage of a ballot between said feed-rolls.
17. The combination with a rotatable pinion and a registering device, of a swinging rack operatively connected with said registering device and normally out of engagement with said pinion, a lever pivoted at one 15 end to a supporting-framework, a pin projecting from said lever and supporting said rack, and means determined by the passage 20 of a ballot through the machine for raising the free end of said lever to carry the rack into engagement with the pinion.
18. The combination with a rotatable pinion, and a registering device, of a swinging rack operatively connected with said registering device and normally out of engagement with said pinion, a lever pivoted at one 25 end to a supporting-framework, a pin projecting from said lever and supporting said 30 rack, means for raising the free end of said lever, determined by the passage of a ballot through the machine, to carry the rack into engagement with said pinion, a shoulder on

said rack arranged to allow the rack to fall out of engagement with said pinion and engage said supporting-pin to hold said rack from longitudinal movement. 35

19. The combination with a rotatable pinion and a registering device, of a swinging rack operatively connected with said registering device and normally held out of engagement with said pinion, a lever pivoted at one end to a supporting-framework, a pin projecting from said lever and supporting said rack, means for raising the free end of 40 said lever to carry the rack into engagement with said pinion, means for raising and lowering the free end of said lever determined by the passage of a ballot through the machine, a shoulder on said rack to engage the rack- 45 supporting pin, and means for lifting the rack out of engagement with said pin. 50

20. In an apparatus of the class described, the combination of a pair of grooved feed-rolls, a canceling-roll engaging a groove in 55 said feed-rolls, a yielding inking-roll normally out of engagement with said canceling-roll, a shaft carrying said canceling-roll, movable bearings for said shaft, whereby said canceling-roll is capable of being moved 60 into contact with said inking-roll.
